UNITED STATES PATENT OFFICE.

THOMAS N. NORTON, OF CHICAGO, ILLINOIS.

POULTRY-HOVER.

1,179,553.

Specification of Letters Patent. Patented Apr. 18, 1916.

Application filed March 3, 1915. Serial No. 11,801.

To all whom it may concern:

Be it known that I, THOMAS N. NORTON, a citizen of the United States, and a resident of the city of Chicago, county of Cook, and State of Illinois, have invented certain new and useful Improvements in Poultry-Hovers, of which the following is a specification.

My invention relates to improvements in poultry hovers, and has for its object the provision of an improved construction of this character which is simple and efficient in use and capable of economical manufacture.

The invention consists in the combinations and arrangements of parts hereinafter described and claimed.

The invention will be best understood by reference to the accompanying drawing forming a part of this specification, and in which,

Figure 1 is a vertical section of a construction embodying my invention, and Fig. 2, a top plan view of the same.

The preferred form of construction, as illustrated in the drawing, comprises a circular sheet metal cover member 3 having four slots 4 positioned therein adjacent the edges thereof, said slots being arranged in diametric pairs on diameters at right angles to each other. A supporting frame 5 is formed of two strips or straps of metal bent into substantially U-form, the ends of said straps being passed through the slots 4, and said straps being crossed centrally, as shown. A central tuft 6 of feathers or other suitable fluffy material, is arranged under cover member 3 and is provided with a perforated head 7 through which a bolt 8 is passed, said bolt passing also through said cover member and through suitable perforations provided in the crossed frame members 5 at their point of crossing. A nut 9 serves to secure the tuft head 7 to the under side of the cover member 3 and nuts 10 and 11 serve to secure the bolt 8 to the frame members 5. Side tufts 12 are provided with wooden heads 13 secured in position to the under side of cover member 3 by driving nails 14 through said cover member into said heads. The cover member 3 is further stiffened and strengthened by means of annular beads 15, as indicated. This forms a construction which may be readily collapsed

or put together, is highly efficient in use,

and is capable of very economical manufacture.

In order to form a run-way for the chicks or other poultry, a strip or band of wire mesh material 16 is provided of a length somewhat greater than the circumference 60 of the cover member 3 and equipped with a hook 17 by means of which the ends of said band may be adjustably secured together. When the ends of the band are but 65 slightly overlapped, as in Fig. 2, and said band positioned eccentrically with reference to the cover member, sufficient run-way is provided for feeding and watering the chicks. At night, the ends of the band 70 16 are overlapped until the same is drawn closely about the hover and secured in this position by means of hook 17 whereupon rats or other inimical animals will be positively excluded.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope 80 of the appended claims.

Having described my invention what I claim as new and desire to secure by Letters Patent is:

1. A hover comprising a cover member; a supporting frame; a bolt passing through said cover member and detachably connected with said frame; a central tuft secured to the under side of said cover by said bolt; and a plurality of side tufts secured to the under side of said cover member, substantially as described.

2. A hover comprising a cover member; a supporting frame; a bolt passing through said cover member and detachably connected with said frame; a central tuft secured to the under side of said cover member by said bolt; and a plurality of side tufts secured to the under side of said cover member by means of nails driven therethrough, substantially as described.

3. A hover comprising a cover member; a supporting frame consisting of two crossed substantially U-shaped members; a bolt passing through said cover member and detachably connected with said frame at the

point of crossing of said members; a central tuft secured to the under side of said cover by said bolt; and a plurality of side tufts secured to the under side of said cover member, substantially as described.

4. A hover comprising a cover member; a supporting frame consisting of two crossed substantially U-shaped members; a bolt passing through said cover member and detachably connected with said frame at the point of crossing of said members; a central tuft secured to the under side of said cover by said bolt; and a plurality of side tufts secured to the under side of said cover member by means of nails driven therethrough, substantially as described.

5. A hover comprising a circular cover member having slots adjacent the edges thereof, said slots being arranged in diamet-

ric pairs; a supporting frame consisting of two metal straps bent into substantially U-form, crossed and passed through said slots; a central tuft having a perforated head; a bolt passed through said head, centrally through said cover member and detachably secured to said frame members at their point of crossing; and a plurality of side tufts secured to the under side of said cover member by means of nails driven therethrough, substantially as described.

In testimony whereof I have signed my name to this specification in the presence of two subscribing witnesses.

THOMAS N. NORTON.
